(57) **CLAIM**

The ornamental design for a parasol stand, as shown and described.

DESCRIPTION

FIG. 1 is a first perspective view of a parasol stand showing our new design;

FIG. 2 is a second perspective view thereof;

FIG. 3 is a front elevation view thereof;

FIG. 4 is a rear elevation view thereof;

FIG. 5 is a right elevation view thereof;

FIG. 6 is a bottom view thereof; and,

FIG. 7 is a top view thereof.

The broken lines depict portions of the parasol stand that form no part of the claimed design.

1 Claim, 7 Drawing Sheets
